FIG. 1.

FIG. 2.

3

FIG. 4.

FIG. 3.

Inventor:
William Schuerg

Patented May 1, 1923.

UNITED STATES PATENT OFFICE.

WILLIAM SCHUERG, OF MENARD, TEXAS.

TRUSS.

Application filed December 16, 1921. Serial No. 522,963.

To all whom it may concern:

Be it known that I, WILLIAM SCHUERG, a citizen of the United States, and a resident of Menard, in the county of Menard and

5 State of Texas, have invented certain new and useful Improvements in Trusses, of which the following is a specification.

The present invention relates generally to trusses, and more particularly to trusses of

10 that nature in which provision is made for the alleviation of what are known as scrotal ruptures, the primary object being the provision of a simple inexpensive form of truss which may be firmly and evenly maintained 15 in proper place with minimum discomfort.

A further object is the provision of a truss of the above nature having the construction which I will now proceed to describe.

20 With reference to the accompanying drawing which forms a part of this specification and in which,

Figure 1 is a front view of the complete truss including the leg and body straps,

25 Figure 2 is an enlarged front view with the leg and body straps removed, and

Figures 3 and 4 are vertical and horizontal sections taken respectively on lines 3—3 and 4—4 of Figure 2.

30 Referring further to these figures my invention proposes a truss in which a substantially flat pad A', which may be formed either of cotton or wool, but which is preferably loosely spun, knitted or woven, is shaped and extended to project across the inner face of a back plate including both a main section A and an auxiliary or scrotal section G, and which is preferably extended at its edge for a slight distance around the outer edges of the sections of the back plate.

40 By reference to Figure 2, in particular it will be noticed that both of these sections of the back plate, which are preferably formed of tin or similar material, having openings punched therein, by means of which the back plate and the pad may be joined by stitching, the stitch receiving openings being indicated at J of the section G of the back plate and the

45 stitches themselves being indicated at A² on the main section A in Figure 2.

The main section A of the back plate is generally rectangular, its sides and its base having rolled edges C which confine a wire insert B acting to reinforce the entire back plate section as well as to perform certain

other functions for which purpose the rolled edge C is cut away at points intermediate the side edges and the lower edge, the wire B being at these points bent to form forwardly outstanding attaching loops D.

Through the side attaching loops D are secured the bent ends of a cross bar E extending across the front face of the main section A in spaced relation thereto and having at its central portion a clasp F, the central portion of whose T-shaped body depends along the central portion of the back plate and the ends of whose lateral extensions are coiled around the cross bar E with their terminals 70 engaging the front face of the black plate to resiliently hold the central prongs against the latter.

At opposite sides of this central clasp F designed for the detachable support of the engaged ends of the leg strap, as herein-after described, the cross bar E provides for the reception of hooks P to which are connected the tabs Q' (see Figure 1) of the body encircling strap Q, the latter having 80 buckles which the tabs Q' adjustably engage.

Adjacent to one side of the main back plate section A the cross bar E also provides for the connection of one bent end of an L shaped strap holding rod whose opposite bent end is engaged through the lower loop D of a wire B and whose lower portion provides for the permanent reception at K' of one end of one leg strap O, the opposite 90 end of which leg strap is adapted to adjustably engage a buckle at the free end of the other leg strap end.

The auxiliary or scrotal section G of the back plate is, like the main section A, provided along its opposite sides with rolled edges I enclosing a reinforcing wire H which is exposed across the lower edge of this section in order to receive a permanent hold at L, the lower or inner end of the leg strap N, it being noted that this section G of the back plate is approximately L shaped and extends around one lower corner of the main section A. It will also be noted that the reinforcing wire H of the section G is 100 extended at its ends by the ends of this section and provided with terminal hooks whereby it may be engaged with one hooked end of the cross bar E and with the lower 110 outstanding rod D of the wire B, thus forming flexible links connecting between the auxiliary section G and the main section A.

By reference to Figure 1 in particular, it would be noted that a cross web M connects the rod or inner portion of the two leg straps N and O near the permanently connected 5 ends of these straps at K' and L, so as to prevent the straps from turning, twisting or curling as well as to prevent slipping downwardly on either leg in use, and in particular to prevent the truss from being pulled 10 sideways as often results from the use of only one strap and even where two straps are used without my improved cross connection. In this way I propose to render the device more uniformly stationary and comfortable. 15 It will thus be observed that with the two leg straps both permanently connected at their lower or inner ends, one to the main section of the back plate, and the other to the auxiliary section of the back plate, having 20 their upper or free ends adjustably engageable with one another after passage around the legs, the adjustably connected ends of the leg straps are held at the front of the truss and prevented from falling by virtue 25 of their disposition between the central depending prongs of the clasp F which may be easily raised to admit the connected ends of the straps from beneath, and also to permit of removal of the connected strap 30 ends.

In this way and in consideration of the body and encircling strap Q it is obvious that in use both the lower and upper portions and the pad will be subjected to the 35 tension of the body and the leg strap, and that in addition to this the central portion of the truss will have a firm even pressure to the adjustable connected ends of the leg straps so that the entire device may be utilized 40 with maximum efficiency and minimum discomfort.

I claim:—

1. A truss including a pad, a back plate 45 consisting of a main section and a separate scrotal section flexibly connected to the main section, and lying in substantially the same plane therewith and flexible attaching connections extending from both of said back plate sections, said pad extending across 50 both the main and scrotal sections of the back plate.

2. A truss including a back plate, inflexible connected sections, one of which is approximately rectangular and the other of 55 which is substantially L shaped and extends around one lower corner of the first section and is flexibly joined to said first section, a pad extending across both of said back plate sections and attached thereto, and flexible attaching connections leading from 60 the pad.

3. A truss including a back plate, inflexible connected sections, one of which is approximately rectangular and the other of 65 which is substantially L shaped and extends

around one lower corner of the first section and is flexibly joined to said first section, a pad extending across both of said back plate sections and attached thereto, including an adjustable body strap engaged with the main section of the back plate and leg encircling straps, one extending from the lower portion of the main back plate section and the other extending from the lower portion of the auxiliary back plate section, said leg encircling straps having adjustably connected ends extending across the main back plate section. 70 75

4. A truss including a back plate, inflexible connected sections, one of which is approximately rectangular and the other of which is substantially L shaped and extends around one lower corner of the first section and is flexibly joined to said first section, a pad extending across both of said back plate sections and attached thereto, including an adjustable body strap engaged with the main section of the back plate and leg encircling straps, one extending from the lower portion of the main back plate section and the other extending from the lower portion of the auxiliary back plate section, said leg encircling straps having adjustably connected ends extending across the main back plate section, and means carried by the main back plate section to engage and detachably hold the said connected ends of the leg straps. 80 85 90 95

5. A truss consisting of a back plate having attaching means extending therefrom and including a main section, and a substantial L shaped auxiliary section extending around one lower corner of the main section and flexibly joined at its opposite ends to one side and the lower edge of the main section, and a pad extending across both of said sections. 100 105

6. A truss including a pad, a back plate having attaching means and including two sections across both of which said pad extends, one of said sections having rolled edges, and a reinforcing wire in the rolled edges extended at its ends beyond said section, and flexibly connected to the other section. 110

7. A truss including a pad, a back plate attached to the pad and having a cross bar upon its outer face, a clasp centrally of the cross bar, a body reinforcing strap and adjustable in connection with the cross bar at 120 opposite sides of said clasp, and leg straps permanently joined at one end to the lower portion of the back plate, having their opposite ends provided with adjustably connected sections and adapted for detachable 125 engagement beneath the said clasp of the cross bar. 115

8. A truss including a pad, a back plate connected to the pad and including flexible joined sections, one of which extends to one 130

side of and below the other, a body encircling strap adjustable in connection at its opposite ends with the upper portion of the upper back plate section, a pair of leg encircling straps, one extending from the lower portion of each of the back plate sections, said leg encircling straps having adjustable connections at their opposite ends for engagement across the face of the upper section, and a clasp approximately at the center of the upper back plate section for detachable engagement to the said adjustably connected ends of the leg straps. 9. A truss including a pad, a back plate connected to the pad and including flexible joined sections, one of which extends to one side of and below the other, a body encircling strap adjustable in connection at its opposite ends with the upper portion of the upper back plate section, a pair of leg encircling straps, one extending from the lower portion of each of the back plate sections, said leg encircling straps having adjustable connections at their opposite ends for engagement across the face of the upper section, and a transverse web connecting the said leg encircling straps adjacent to the lower portions of the back plate sections. 20 25

10 15 9. A truss including a pad, a back plate connected to the pad and including flexible
